UNITED STATES PATENT OFFICE.

J. E. WITHERS, OF TORONTO, CANADA WEST.

IMPROVEMENT IN MACHINES FOR MAKING PLUG-TOBACCO.

Specification forming part of Letters Patent No. 72,578, dated December 24, 1867.

To all whom it may concern:

Be it known that I, J. E. WITHERS, of Toronto, Canada West, have invented a new and Improved Machine for Making Plug-Tobacco; and I do hereby declare that the following is a full, clear, and exact description thereof, which will enable others skilled in the art to make and use the same, reference being had to the accompanying drawings, forming part of this specification.

This invention relates to a machine for making plug-tobacco; and consists of a series of rollers pressing the tobacco in troughs running on flange-rollers. A large wheel revolving in a transverse direction shifts the troughs onto a series of rollers revolving in the opposite direction, by which they are carried back to the end from which they started. An inclined knife removes the tobacco from the troughs when sufficiently pressed.

In the accompanying drawings, Figure 1 is a front, and Fig. 2 a back, view of my machine. Fig. 3 is a top view thereof; Fig. 4, a vertical section, longitudinal at line $x-x$ of Fig. 3; and Fig. 5, a transverse section at line $y-y$ of Fig. 4.

Similar letters of reference indicate like parts.

A is a wall or framing, in which the driving-wheel B is journaled, as also the sheave-pulleys C C C and pulleys C' C' C', driven by the endless band D, in manner as shown, or by any equivalent method, by which a simultaneous motion in the same direction is imparted to C C C, and to the flange-rollers E E E on the opposite side of the journal-frame A. The sheave-pulleys C C C are of the same size. The flange-rollers E E E are also of one size and arranged on the same level.

F F are troughs, in which the tobacco is laid and fed to the machine at end Z, between the rollers G G G (journaled in A) and flange-

rollers E E E. On the troughs reaching the knife K the tobacco is by it removed to the shelf H, while the trough passes on under the knife, the slot l affording room for the side of the trough to pass. When the trough is emptied by the knife it is pressed on by the trough next behind it until its end is clear of the journal-frame in which the reverse rollers M M are journaled, when the large wheel N, revolving transversely, feeds the trough to the rollers M M M, by which they are carried back to the end Z of the machine.

The wheel N and rollers M M M may be driven by the endless bands P Q, or by gear and miter wheels, or by any other known mechanical device for changing the direction of motion.

Having thus described my invention, what I claim as new, and desire to secure by Letters Patent, is—

1. The flange-rollers E E E, revolving in the same direction, in combination with the rollers G G G, in manner substantially as and for the purposes described.
2. The inclined knife K, removing the tobacco or other substance from, and in combination with, the troughs F to the platform H, or other place of deposit, substantially as described.
3. The flange-rollers E E E, revolving in the same direction, in combination with the wheel N, revolving in a transverse direction, substantially as and for the purposes described.
4. The flange-rollers E E E, revolving in the same direction, in combination with the rollers M M, revolving in a reverse direction, in manner and for the purposes substantially as herein shown and described.

J. E. WITHERS.
